UNITED STATES PATENT OFFICE

2,505,310

BABY CREEPER

Wilford Le Roy Thompson, Baton Rouge, La.

Application July 11, 1946, Serial No. 682,887

2 Claims. (Cl. 155—22)

1

This invention relates to baby creepers, the primary object of the invention being to provide a baby creeper which may be inverted and used as a bathtub supporting frame for convenience in bathing the baby.

Another object of the invention is to provide a baby creeper and bathtub frame which is so constructed that the bathtub supported thereby may be extended providing a drying table on which the baby may be dried after bathing.

Still another object of the invention is to provide a baby creeper embodying a frame comprising upper and lower ring members and tubular connecting rods whereby the frame may be readily set up or dismantled to facilitate transportation and storage of the baby creeper.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred forms of the invention have been shown.

Referring to the drawings:

Figure 1 is an elevational view of the device when used as a baby creeper.

Figure 2 is a plan view thereof.

Figure 3 is an elevational view of the creeper when inverted and used as a bathtub frame.

Figure 4 is a plan view of the device when used as a bathtub.

Figure 5 is a transverse sectional view through the bathtub and upper portion of the frame.

Figure 6 is a transverse sectional view taken at right angles to Figure 5.

Figure 7 is a transverse sectional view illustrating the flap at one side of the bathtub as extended over the frame and secured by the tie strings.

Figure 8 is a sectional view taken on line 8—8 of Figure 2.

Figure 9 is a sectional view taken on line 9—9 of Figure 2.

Figure 10 is a sectional view taken on line 10—10 of Figure 2.

Figure 11 is a sectional view taken on line 11—11 of Figure 4.

Referring to the drawings in detail the baby creeper embodies a frame including an upper section 5 and a lower section 6, the upper section embodying an outer ring 7 and an inner ring

2

8, the rings being held in spaced relation with respect to each other by means of the pipes 9.

The lower section 6 embodies a ring which is of a diameter appreciably greater than the diameter of the outer ring 7 of the upper section, as clearly shown by the drawings.

Extending downwardly from the upper section of the baby creeper are pins 10, the pins 10 being arranged in predetermined spaced relation with respect to each other and so constructed that they extend into the ends of the tubular supporting legs 11 which have their lower ends 12 extended at acute angles and fitted over pins 13 that extend upwardly from the lower section 6, connecting the upper and lower sections of the baby creeper.

The lower ends of the pins 13 are formed with bores to accommodate the shanks 14 of the casters 15, whereby the frame may be conveniently rolled over a supporting surface.

Hooks 16 are secured to the inner ring 8 of the upper section of the bathtub and receive the loops at the upper ends of the coiled springs 17, the lower ends of the coiled springs being secured 25 around the ring 18 forming the upper supporting section of the basket 19 which provides the seat for the baby creeper. The basket 19 also includes a lower ring 20, the rings 18 and 20 being connected by a length of canvas material 21 so that the basket may be readily and easily collapsed to facilitate the transportation and storage thereof. The bottom of the basket is indicated by the reference character 22 and is also formed of canvas, the bottom being provided 30 with leg openings 23, through which the baby's legs extend while seated within the basket. It will be seen that due to this construction, the lower section of the frame being appreciably larger than the upper section, the frame will 35 be securely supported in an upright position against being toppled over by the baby or infant seated in the basket.

When the device is to be used as a bathtub, the basket 19 is removed and the entire frame 45 inverted, that is to say, the upper section 5 is positioned to provide the support for the lower section 6 which now becomes the upper section of the bathtub frame.

The casters 15 are removed and the ends of the bathtub frame are extended into the caster openings. The ends of the bathtub frame which extend downwardly are indicated by the reference character 26. The bathtub frame embodies rods 27 which are connected by means of 50 the rods 28, the rods constituting the frame

around which the upper edge of the canvas bathtub 28 is secured. The bottom of the bathtub comprises a rectangular frame 29 to which the lower end of the bathtub is secured, holding the bathtub in an extended position. It will, of course, be understood that the bathtub proper is constructed of flexible waterproof material such as canvas or the like so that when the bathtub has been removed from the frame, the bathtub may be readily collapsed and folded into a small and compact article for storing.

When the device is to be used as a bathtub frame, tubular supporting members 30 are provided and support the sections 5 and 6 in spaced relation with respect to each other, the tubular supporting members 30 being substantially longer than the tubular supporting members or legs 11, so that the bathtub will be supported at an elevation for the convenience of the person bathing the baby in the bathtub.

At the ends of the bathtub are pockets 31 in which soap, washcloths, brushes or the like may be conveniently stored for use.

A further important feature of applicant's invention is the arrangement of the flaps 32 which have their outer edges curved to fit over ring section 6, where they are stretched and held in such stretched condition by means of the tie strings 33.

After the baby has been bathed, the drying sheet 34, which is secured along one edge of the bathtub, is moved to a position directly over the bathtub where it is secured by means of the tie strings 35, providing a table or drying surface on which the baby may be dried.

From the foregoing it will be seen that due to the construction shown and described, I have provided a device which may be used either as a baby creeper or a bathtub by merely inverting the frame of the device and making a few slight adjustments as described.

Having thus described the invention what is claimed is:

1. A device of the class described, comprising a frame embodying spaced horizontally disposed circular end members arranged one above the other, one circular end member being substantially large, the other circular end member embodying an outer ring and an inner ring, horizontal pipes connecting the outer and inner rings, tubular members connecting the end members, said tubular members being connected with said inner ring, the outer ring being spaced an appreciable distance from the tubular members, providing a support for the frame.
2. A device of the class described, comprising a frame embodying spaced horizontally disposed circular end members, one circular end member being substantially large, the other circular end member embodying an outer ring and an inner ring, horizontal pipes connecting the outer and inner rings, tubular members connecting the end members, said tubular members being connected with said inner ring, the outer ring being spaced an appreciable distance from the tubular members providing a base for the frame, and supporting hooks connected with 25 said inner ring.
